Primary Examiner — Charles D Hanson

(57) **CLAIM**

The ornamental design for an implant shell having internal, global ribs, as shown and described.

DESCRIPTION

FIG. 1 is a perspective view of an implant shell having internal, global ribs, showing our new design;

FIG. 2 is a side view of the implant shell having internal, global ribs shown in FIG. 1;

FIG. 3 is a top plan view of the implant shell having internal, global ribs shown in FIG. 1;

FIG. 4 is a bottom view of the implant shell having internal, global ribs shown in FIG. 1; and,

FIG. 5 is a partial cross-sectional view of the implant shell having internal, global ribs shown in FIG. 3.

1 Claim, 4 Drawing Sheets
